UNITED STATES PATENT OFFICE.

PHILIP KLEEBERG, OF NEW YORK, N. Y.

DESIGN FOR EMBROIDERY.

SPECIFICATION forming part of Design No. 20,652, dated March 31, 1891.

Application filed February 19, 1891. Serial No. 382,125. Term of patent 3½ years.

To all whom it may concern:

Be it known that I, PHILIP KLEEBERG, a citizen of the United States, residing at New York city, in the county and State of New

5 York, have invented a new and original Design for Embroidery, of which the following is a specification, reference being had to the accompanying drawing, forming a part thereof, wherein the design is shown in plan view.

10 The design consists of a number of semi-circular connected figures *a*, grouped to simulate crescent figures *A*, the said crescent fig-

ures producing a festoon effect, and upon a surface representing a field inclosed by the crescent figures figures *B* are arranged, the 15 said figures simulating the fleur-de-lis.

I claim—

The design for embroidery, substantially as herein shown and described.

PHILIP KLEEBERG.
